JACKET OR THE LIKE

Hans Jakob Bucking, Alsfeld in Hessen, Germany

Application July 13, 1953, Serial No. 25,910

Claims priority, application Germany March 28, 1953

Term of patent 7 years

(Cl. D3—4)

To all whom it may concern:

Be it known that I, Hans Jakob Bucking, a citizen of Germany, residing at Alsfeld in Hessen, Germany, have invented a new, original, and ornamental Design for a Jacket or the like, of which the following is a specification; reference being had to the accompanying drawing, forming part thereof.

The figure is a front view of a jacket or the like according to the present invention. The back of the jacket is plain and unornamented.

I claim:

The ornamental design for a jacket or the like, as shown and described.
